Application January 31, 1941, Serial No. 376,828

13 Claims.

(Cl. 237—8)

Broadly speaking, our invention particularly relates to a furnace, primarily designed for solid fuel-burning purposes, which includes a heat-transfer device; and to control means for said furnace adapted automatically to pass the gases of combustion of the fuel in said furnace to the heat-transfer device when the temperature of the medium heated thereby indicates a demand for heat and substantially to prevent a flow of said gases to the heat-transfer device when the heat demand has been satisfied.

It is a first object of our invention to provide a furnace having a plurality of passages communicating with the combustion chamber thereof, one of said plurality of passages including a heat-transfer device and a second of said passages constituting a by-pass, and means for controlling the flow of the products of combustion through said plurality of passages.

Another object of our invention resides in providing a furnace comprising a plurality of passages communicating with the combustion chamber thereof and with a stack or exhaust passage, one of said passages including a heat-transfer device for heating one medium and a second of said passages including a heat-transfer device for heating a second medium, and means responsive to the temperatures of said mediums for controlling the flow of the products of combustion to the respective heat-transfer devices.

Another object resides in providing a furnace of the character above pointed out in which one of the plurality of passages constitutes a by-pass and in which the control means therefor is so constructed and arranged that when the temperature of one medium to be heated indicates a demand for heat, said control means will operate to permit the gases of combustion to flow to the heat-transfer device wherein heat is obtained for raising the temperature of said medium and for substantially preventing the flow of said gases through said by-pass, and, when the heat demand of the medium is satisfied, will operate substantially to prevent the flow of said gases to said heat-transfer device and to permit the gases to flow through said by-pass.

Another object of our invention resides in providing a furnace and controls therefor of the foregoing character in which an electrically operated draft-producing means is employed which, when the controls so permit, will produce a forced flow of gases of combustion through either the by-pass passage or the passages including the heat-transfer devices; and in which the control means includes a stack switch or similar

device which controls the draft producing means, irrespective of the other control means, to produce a draft through the by-pass and fuel bed to maintain the fuel bed temperature sufficiently high to sustain continued combustion of the fuel under idling conditions.

More specifically, it is an object of our invention to provide a furnace and controls therefor of the foregoing character in which valves are employed for controlling the flow of gases of combustion through the respective passages, the valves and the operating means therefor being so correlated that flow of the gases through the by-pass is substantially prevented when one of the valves opens to permit the gases to flow through one of the heat-transfer devices, the valve for the by-pass passage being held in open position when the gases are not permitted to flow to any of the heat-transfer devices.

With these and other objects in view, our invention includes the novel elements and the combinations and arrangements thereof described below and illustrated in the accompanying drawings, in which preferred embodiments of our invention are shown, and in which—

Fig. 1 is a sectional, elevation view of a furnace embodying one form of our invention and illustrating somewhat diagrammatically the controls therefor;

Fig. 2 is a fragmentary, sectional elevation view of the furnace of Fig. 1, showing the controls actuated to provide a flow of gases of combustion through one of the heat-transfer devices;

Fig. 3 is a view similar to Fig. 2 but showing the controls actuated to provide a flow of gases through a second of the heat-transfer devices;

Fig. 4 is a fragmentary, sectional elevation view showing a modified form of furnace and controls;

Fig. 5 is a wiring diagram of our control system illustrating somewhat schematically some of the control elements in perspective;

Fig. 6 is a wiring diagram similar to Fig. 5 but showing various of the elements in different positions; and

Fig. 7 is a fragmentary, sectional elevation view of our furnace showing a preferred location of one of the controls.

Referring to the drawings and first to Fig. 1, 1 indicates generally a furnace comprising a combustion chamber 2 within which fuel may burn upon a grate 3. The surface of the bed of fuel is indicated in dot-dash lines at 4. Fuel may be delivered to the fuel bed through a supply passage or magazine 5 and air for combustion purposes is admitted through an opening 6 in the

ash pit. An air inlet valve 7, which is operated by a solenoid 8, serves to control the flow of air through the opening 6. In the form of furnace herein illustrated, passage 9, which communicates with the combustion chamber 2 and through which hot gases of combustion may flow, extends first rearwardly from above the fuel bed and downwardly and then communicates with a plurality of preferably vertically extending passages 10, 11 and 12.

The passage 12 includes a heat-transfer device, indicated generally at 13, comprising a plurality of tubes through which the gases of combustion may flow and spaces about said tubes which are adapted to receive air or water, for example, for house heating purposes. The upper end of the heat-transfer device 13 communicates through an orifice 14 with a breeching or exhaust passage 15 from which the gases may pass to atmosphere. In orifice 14 is formed a seat for a valve element 16 which, as hereinafter explained, serves to control the flow of the gases through the passage 12 and heat-transfer device 13.

Passage 11 also includes a heat-transfer device indicated generally at 17 through which the gases of combustion may pass and which is adapted to transfer heat from said gases to water, for example, for domestic hot water purposes. The upper end of the device 17 also communicates with the breeching 15 through an orifice 18 in which is formed a seat for a valve element 19. Valve 19 serves to control the flow of gases through passage 11 and heat-transfer device 17.

It will be understood that we have more or less diagrammatically illustrated the heat-transfer devices 13 and 17 mainly for purposes of illustration and that any type or form of heat-transfer device may be employed.

The passage 10, in accordance with our invention, communicates with passage 9 and with the breeching 15 and preferably does not include a heat-transfer device. The upper end of passage 10 communicates with breeching 15 through an orifice 20 in which is formed a seat for a valve 21 which serves to control the flow of gases through passage 10.

The furnace, about the combustion chamber, passages therein and heat-transfer devices and between said devices, is preferably insulated as illustrated and the passage 10 may be formed in the insulation.

In a furnace embodying the preferred construction and relative arrangement of the passages 10, 11 and 12, the passage 10 will communicate with passage 9 in a zone nearer the combustion chamber than those zones in which the passages 11 and 12 communicate with passage 9. By relatively arranging the passages in this manner, the gases of combustion will flow directly to and through the passage 10 when the valve elements 16, 19 and 21 occupy the positions shown in Fig. 1 and there will be no tendency of these hot gases to flow to either of the passages 11 and 12.

A fan 22, driven by motor 23, is arranged in the breeching 15 and functions to provide a forced draft or flow of gases of combustion from the combustion chamber and through the passages communicating therewith and with the breeching 15 when the valves so permit. The manner in which motor 23 and also solenoid 8 are connected in the control circuit of our furnace will be hereinafter pointed out.

For the sake of clearness in illustration, we have shown the cables, hereinafter described, which are connected with the valves 16, 19 and 75

21, respectively, as passing through the upper side of the breeching 15. It will be understood, however, that in practice, we prefer to pass the cables downwardly on the exterior of the duct 5 and to connect them to lever arms mounted on rods which pass through bearings in the side of the stack, and to connect lever arms which are also mounted on said shafts, but disposed within the breeching, with a cable which in turn is 10 fastened to said valves.

As will be hereinafter more particularly pointed out, a thermostat which is mounted in heat responsive relation to the medium such as water or air which derives its heat from the 15 heat-transfer device 13, controls an electrical circuit to a control motor 24 which, through the medium of a speed-reducing mechanism 25 (see Fig. 5), drives a cam shaft 26 on which is mounted a lever arm 27. Referring back to Fig. 1, crank arm 27 is connected through an adjustable connector 28 to a cable 29 which passes over pulleys 30 and 31 and thence downwardly and is 20 connected to the valve 16. When the thermostat does not call for heat, arm 27 occupies the raised position and the valve 16 closes the orifice 14 thereby preventing the flow of gases of combustion through the heat-transfer device 13. However, when the thermostat indicates a demand for heat, motor 24 will operate to move the 25 arm 27 through substantially 180° thereby elevating the valve 16 and permitting gases to flow through the passage 12 and heat-transfer device 13.

In accordance with our invention, the valve 35 16, and valve 19, as hereinafter described, are so correlated with valve 21 that when either valve 16 or 19 is elevated, valve 21 will be positioned to effect a closure of the orifice 20 of passage 10, and when both valves 16 and 19 are in closed position, valve 21 will lie in open position. In the embodiment illustrated, we accomplish 40 this correlated operation of valve elements by connecting valve 21 through a cable 32 which is connected to one end of a lever arm 33, pivoted intermediate the ends at 34. To the other end of lever 33 is connected a weight 35 and a cable 36 which passes upwardly and over pulleys 37 and 38 and thence downwardly and is connected to one end of a lever arm 39. Lever 39 is pivoted at 45 a point intermediate the ends thereof and the other end thereof is connected as indicated at 40 to the cable 29 between valve 16 and pulley 31.

With the correlation of elements above described, it should be evident that when the arm 27 occupies the position illustrated in Fig. 1 that weight 35 will be free to move downwardly and thereby maintain the valve 21 in elevated position as shown. However, when the arm 27 is moved through approximately 180° to the position illustrated in Fig. 2, cable 29 will elevate valve 16 and pivot arm 39 in a clockwise direction thereby, through the medium of cable 36, elevating the weight 35 and causing arm 33 to pivot in a counter-clockwise direction to seat the valve 21 and effect a substantial closure of the orifice 20.

Assuming that the heat-transfer device 17 is used for domestic hot water heating purposes, as hereinbefore indicated, an aquastat as indicated generally at 41 is disposed in heat responsive relation to the water heated in the device 17. For exemplary purposes, we have shown the aquastat 41 associated with a pipe 42 which it will be understood is connected with the heat-transfer

device 17. The aquastat may comprise a Sylphon bellows 43 which expands and contracts in accordance with changes in the temperature of the water in the pipe 42. Bellows 43 is connected with a lever 44, pivoted at one end at 45 and connected at its other end to a cable 46 which passes over pulleys 47 and 48 and thence downwardly and is connected to the valve 19. When the temperature of the water within the heat-transfer device 17 or pipe 42 falls to a predetermined minimum, bellows 43 will contract sufficiently to reverse the inclination of the lever arm 44 and thereby, through the medium of cable 46, elevate valve 19. When this occurs, the gases of combustion may flow through passage 11 and heat-transfer device 17.

One end of a lever arm 49 is connected to cable 46 as indicated at 50. Lever 49 is pivoted intermediate the ends thereof and its other end is connected to a cable 51 which passes over a pulley 52 and is connected as indicated at 53 to that portion of the cable 36 which lies between the pulleys 37 and 38. Therefore, when the aquastat functions to raise the valve 19 from its seat, it will also cause lever 49 to pivot in a clockwise direction and through cables 51 and 36 elevate weight 35 and produce rotation of lever 33 in a counter-clockwise direction sufficient to seat the valve 21 as illustrated in Fig. 3.

From the foregoing, it should be apparent that when either the thermostat or the aquastat function to elevate the valve 16 or the valve 19, the valve 21, in each case will be moved to its seated position effecting a substantial closure of the orifice 20 of passage 10. Furthermore, when both valves 16 and 19 occupy their closed positions, the valve 21 will be raised from its seat. It will further be understood that the thermostat and the aquastat may so operate as to cause the valves 16 and 19 to be elevated from their seats during the same period of time and, of course, when this occurs the valve 21 will occupy its closed position as it does when either of said valves 16 or 19 is elevated.

The electrical control system for our furnace and the manner in which the various electrical elements are preferably connected in said system will best be understood by referring to Figs. 5 and 6. Power is derived from the main lines 54 and 55 to which are connected conductors 56 and 57. Between conductors 56 and 57 is connected the primary of a transformer 58, one end of the secondary of which is connected through conductor 59 to motor 24, hereinbefore referred to, and the other end of the secondary being connected through conductor 60 to a plurality of contacts 61, 62 and 63. In the drawings, we have shown the conductor 60 as connected to the supports on which the contacts 61, 62 and 63 are, respectively, pivotally supported and it will be understood that these supports and the arms bearing said contacts are of electric conducting material. As hereinbefore indicated, motor 24, through the gear reducing mechanism 25, is adapted to rotate shaft 26 on which arm 27 is mounted and on which are also mounted a plurality of cams. These cams are adapted both to control the circuit to motor 24 and also to control the circuits to motor 23 of fan 22 and the solenoid 8.

Contact 61 is mounted on an arm provided with a boss 64 which is adapted to engage the surface of a cam 65 secured on shaft 26. The cam is provided with a recess 66 which, when the cam occu-

pies the position shown in Fig. 6, permits the boss 64 to enter and break the electrical circuit between the contact 61 and a second contact 67 which is connected through conductor 68 to one contact 69 of a thermostat 70. However, when the cam 66 occupies the position shown in Fig. 5, contacts 61 and 67 will engage each other. A second cam 71 which is secured on shaft 26 is provided with a pair of diametrically opposed recesses 72 and 73. Contact 62 is mounted on an arm provided with a boss 74 which is adapted to enter either the recess 72 or 73. However, as the cam rotates, boss 74 will be forced out of one or the other of said recesses and will ride upon the surface of the cam, holding contact 62 in engagement with a contact 75 which is connected through conductor 76 to the bi-metallic arm of thermostat 70. Conductor 76 is also connected through conductor 77 to one side of the motor 24. A third cam 78, which is also secured on shaft 26 is provided with a projection 79 which is adapted to engage the boss 80 on the arm on which contact 63 is mounted when it occupies the position shown in Fig. 6 and urge contact 63 into engagement with a contact 81 which is connected through conductor 82 to a second contact 83 of the thermostat 70.

The cams and associated contacts, above described, are employed in conjunction with the thermostat 70 to control the operation of motor 24. For example, these elements are illustrated in Fig. 5 in the positions which they will occupy after the bi-metallic arm of the thermostat 70, due to a predetermined drop in temperature of the medium to which it is responsive, has engaged the contact 83 and has caused motor 24 to rotate arm 27 to open valve 16 and permit gases of combustion to flow to the heat-transfer device 13. After the bi-metallic arm 70 of the thermostat has engaged contact 69 the motor 24 will rotate the cams and arm 27 to the positions shown in Fig. 6. It will be understood, of course, that when the arm of thermostat 70 engages either contact 69 or 83 that motor 24, in the embodiment illustrated, will operate to rotate the cams and arm 27 through substantially 180°.

In Fig. 6, the cams and arms operated thereby occupy the positions they will be moved to after the thermostat arm had engaged contact 69. In this position thereof, contacts 61 and 67 and contacts 62 and 75 will be spaced apart but contacts 63 and 81 will lie in engagement with each other. With the parts in these positions and assuming that the temperature of the medium, to which the thermostat 70 is responsive, falls to a predetermined minimum, causing the arm of thermostat 70 to engage contact 83, a circuit to motor 24 will be closed which includes the conductor 60, which is connected to one side of the secondary of transformer 58 and to contact 63, contact 81, conductor 82, contact 83 and the bi-metallic arm in contact therewith, conductor 76 and conductor 77 to one side of motor 24. The motor circuit is completed through conductor 59 to the other side of the secondary of the transformer 58. As the motor 24 rotates the cams from the positions thereof illustrated in Fig. 6, cam 71 will force contacts 62 and 75 into engagement with each other and a parallel circuit will be established between conductor 60 and conductor 77. Cam 71 and its associated contacts, therefore, insure a continued and complete rotation of the cams through approximately 180° or until the recess 73 in cam 71 is moved to a po-

sition permitting the boss 74, associated with the arm on which contact 62 is mounted, to fall therein and break the circuit between contacts 62 and 75. At the same time, of course, the circuit through contacts 63 and 81 will also be broken.

The positions which the cams 65, 71 and 78 will occupy after having so rotated through 180° are shown in Fig. 5. It will be noted that in this latter position of the cams, the circuit to contact 83 of the thermostat will be open and that the parallel circuit through contacts 62 and 75 will also be open and, therefore, a continued engagement of contact 63 by the arm of the thermostat will not effect a further operation of the motor 24. The position of the cams and arm 27, shown in Fig. 5, may be considered the "on" position thereof for house heating purposes. That is, arm 27 has been moved to open the valve 16 and close the valve 21 thereby permitting a flow of the gases of combustion to the heat transfer device 13 which it has been assumed is employed for house heating purposes.

It will be observed that when the cams occupy the positions shown in Fig. 5, that cam 65 will hold contacts 61 and 67 in engagement with each other and thereby close a circuit from conductor 60, through said contacts and conductor 68 to contacts 69 of the thermostat. Therefore, when the heat demand has been satisfied and the bi-metallic arm of thermostat 70 engages contact 69, still another circuit to motor 24 will be completed. This circuit comprises conductor 60, contacts 61 and 67, conductor 68, contact 69 and the bi-metallic arm of thermostat 70, conductor 76 and conductor 77 to one side of motor 24. The other side of the motor circuit is, of course, completed through conductor 59. When this circuit is completed, motor 24 will rotate the cams through substantially 180° whereupon the boss 64 associated with the arm on which contact 61 is mounted will drop into the recess 66 of cam 65 and open the circuit to contact 69 of the thermostat and the motor circuit. During this operation of the motor, of course, a parallel circuit between conductors 60 and 77 will be established through the closing of contacts 62 and 75. Cam 71 and its associated contacts, 62 and 75, is employed to maintain a circuit to motor 24 once the arm of thermostat 70 engages either the contact 69 or 83 and until the cams are moved through approximately 180°.

A fourth cam, cam 84, is secured on shaft 26 and this cam is employed to control the electrical circuit to the motor 23 of the exhaust fan and the solenoid 8 which operates the valve 7, arranged to control the admission of air to the ash pit of the furnace. Conductor 56 which is connected to the main lines is electrically connected with a contact 85 mounted on a pivotally supported arm. The conductor 56 is illustrated as connected to the support for the arm and it will be understood that the support and arm for contact 85 are of electric conducting material. The arm is provided with a boss 86 which is adapted to engage the surface of cam 84, and contact 85 is adapted to engage a contact 87 when the boss 86 is engaged by a projection 88 on the periphery of cam 84. Contact 87 is connected through a conductor 89 to one side of solenoid 8 and the fan motor 23 and the other sides of the solenoid and fan motor are connected with conductor 51 which is, in turn, connected to the power mains.

Therefore, when the thermostat causes an operation of motor 24 to open valve 16 and permit

75 a flow of gases of combustion to the heat exchange device 13, cam 84 will close the circuit through contacts 85 and 87 to the solenoid 8 and fan motor 23. When this occurs, the solenoid 8 will elevate the valve 7 and permit air to flow to the ash pit of the furnace and through the fuel bed thereof. At the same time, motor 23 will be energized and will drive fan 22 to produce a forced draft. Of course, when the heat demand has been satisfied and thermostat 70 effects an operation of motor 24 to close the valve 16 by rotating the arm 27 to the position illustrated in Fig. 6, contacts 85 and 87 will be parted and the solenoid 8 and fan motor 23 de-energized.

The aquastat 41, which is mounted in heat responsive relation to the domestic hot water supply which it has been assumed derives its heat from the heat-transfer device 17, is operable, as hereinbefore explained, to actuate the valve 19, which in turn controls the flow of gases through the heat-transfer device 17, and the valve 21. On the arm 44 of the aquastat, to which the valve-operating cable 46 is fastened, is mounted a switch 90. This switch may be of any desired type and operatively associated with the aquastat in any desired manner. For purposes of illustration, however, we have shown a mercury tube type of switch. To the switch 90 are connected two conductors 91 and 92, the conductor 91 being connected to conductor 89 and conductor 92 being connected to conductor 56. It will be observed that switch 90 is connected in the control circuit in parallel with the contacts 85 and 87 operated by cam 84. Hence, when the aquastat operates to raise the valve 19 whereby to permit a flow of gases through the heat-transfer device 17, it will also operate switch 90 to close a circuit therethrough. When the circuit is closed through switch 90, solenoid 8 and fan motor 23 will be energized and the furnace will operate under substantially the same draft conditions as when the thermostat 70 operated to effect a flow of gases of combustion to the heat-transfer device 13.

It will be observed, as hereinbefore pointed out, that the controls for our furnace are arranged to maintain the valve 21 in open position when all heat demands have been satisfied. The gases of combustion, therefore, may flow through the by-pass or passage 10 and exhaust through the breeching 15. However, although the gases of combustion are exhausted in this manner, there may occur intervals when no heat is demanded and under these idling conditions the temperatures existing in the combustion chamber of the furnace may fall below that sufficient to maintain combustion. In order to maintain the required fuel bed temperature substantially at all times, we provide a switch indicated at 93 in Figs. 5 and 6 which is embodied in what may be generally termed a stack switch. For example, in one type of stack switch, a helical, bi-metallic strip is employed which is adapted to be associated with the stack or breeching of a furnace and functions in response to changes in the temperature within said stack or breeching to close or open the switch proper. Since such switches are of well known construction, we have not herein illustrated the details of our switch but have shown switch 93 mounted on and adapted to be actuated by a bi-metallic arm or heat-responsive element which is adapted to be mounted in heat-responsive relation to the stack or breeching 15 of the furnace. The switch 93 has connected thereto conductors 94 and 95 which in turn are connected respectively to con-

ductor 89 and conductor 56. The switch 93 is, therefore, connected in the control circuit in parallel with switch 90 and the contacts actuated by cam 84 and will function to energize solenoid 8 and fan motor 23 when the temperature conditions to which it is responsive indicate that the fuel bed temperature should be elevated.

In Fig. 4 we have illustrated a modified form of furnace in which but one heat-transfer device is employed as indicated at 96. The furnace is generally similar in construction to that illustrated in Fig. 1 and the passage 9 thereof, through which gases of combustion may flow, communicates with passages 97 and 98. Passage 97 includes the heat-transfer device 96, and the orifice 99 at the top thereof communicates with the breeching 15. Likewise, passage 98 forms a bypass, similar to passage 10 of Fig. 1, and communicates through the orifice 100 with breeching 15. A valve 101 is adapted to form a closure for the orifice 99 and valve 102 is adapted to form a closure for the orifice 100. Assuming that the heat-transfer device 96 is employed for house heating purposes, the control circuit may include the motor 24, its control circuit and associated speed-reducing mechanism and crank arm 27, the motor circuit being in the first instance controlled by a thermostat, and the control circuit being generally similar to that above described. In this case, the arm 27 is connected to a cable 103 which passes upwardly and over pulleys 104 and 105 and thence downwardly and is connected to the valve 101. One end of a lever 106 which is pivoted intermediate the ends thereof is connected to cable 103 as indicated at 107 between the pulley 105 and the valve 101. Intermediate the connection 107 of arm 106 and its pivotal point, a weight 108 is connected to said lever. To the other end of said lever is connected a cable 109 which is fastened to valve 102.

As indicated in full lines in Fig. 4, when the arm 27 is in elevated position, valve 101 will lie in closed position and substantially prevent the flow of gases of combustion to the heat-transfer device 96 while the valve 102 will be elevated and permit the gases to flow through the by-pass passage 98. However, when the arm is moved substantially through 180° to the dotted line position, the valves 101 and 102 will be moved to the positions illustrated in dotted lines thereby substantially preventing the flow of gases through the by-pass while permitting a flow thereof through the heat-transfer device. In this embodiment of our invention we prefer to provide a solenoid for operating the valve which controls the flow of air to the ash pit, an exhaust fan, and a heat-responsive switch operable in response to the temperatures of the products of combustion; the solenoid and the motor for the exhaust fan being controlled substantially in the manner hereinbefore described by the thermostat and the said heat-responsive switch.

It will be observed that when heat is demanded by one or more of the media to be heated that heat will be supplied to that heat-transfer device where heat is required. However, when no heat is demanded by any one of the media, substantially no heat is supplied to the heat-transfer device employed in heating the same. Therefore, heat may be supplied to one or more of a plurality of entirely separate and unrelated media without affecting in any way the temperature of the other, and hence, more uniform and precisely controlled temperature conditions of the media may be maintained.

Furthermore, it is important to note that under conditions of no heat demand the temperature of the fuel bed may be maintained sufficiently high to sustain combustion at a relatively low rate but without supplying heat to the heat-transfer devices, while upon any heat demand the rate of combustion will be increased and the gases of combustion supplied to that heat-transfer device where heat is required. In other words, in our furnace, heat may be supplied to the heat-transfer devices from substantially zero amounts up to those meeting the maximum heat-transfer rate of the units or devices. Furnace operation of this character is extremely desirable for economic and satisfactory year-around performance.

As hereinbefore pointed out, the heat-transfer devices of our furnace are well insulated from each other, and also, they are remote and preferably laterally spaced from the combustion chamber and insulated therefrom. For example, the rear wall of the combustion chamber is of insulating material and extends preferably to an appreciable height above the lower end of the fuel bed. The passage 9, furthermore, communicates with the chamber near the top thereof and extends above the rear wall, thence downwardly and then laterally into communication with the preferably, vertically extending passages 10, 11 and 12. With the above described insulated construction and arrangement of passages, when the valve 7, operated by solenoid 8, and the valve controlling the flow of gases to the heat-transfer device lie in closed position and the fan motor is de-energized, transfer of heat in all ways to the heat-transfer device is impeded to such a great extent that substantially no heat is supplied thereto. Furthermore, due to the retention of heat in the combustion chamber the temperatures above the fuel bed will remain sufficiently high to support combustion over longer periods under the above conditions and, therefore, these temperatures will be maintained sufficiently high over extended periods when no heat is demanded by the media to be heated at a relatively low, average rate of combustion of fuel.

Because, as above set forth, the heat within the combustion chamber and above the fuel bed will be retained therein to a very great extent and, further, in view of the fact that the temperatures in the exhaust passage or breeching of the furnace herein described do not bear any constant relationship to the temperatures existing in the combustion chamber, we prefer to place a heat-responsive switch or the heat-responsive element thereof in direct heat-responsive relation to the temperatures within the combustion chamber rather than in the breeching or exhaust passage of the furnace. This arrangement is illustrated in Fig. 7.

In the embodiment illustrated, a passage 110 is provided which communicates with the combustion chamber in a zone substantially directly above the fuel bed and extends through the furnace to the top thereof. A closure element 111, which may be of heat-insulating material, is supported in a shoulder formed about the passage 110 and supports a heat-responsive switch indicated generally at 112. Switch 112 may be connected in the control circuit of the furnace substantially in the same way as the switch 93. A helical, bimetallic element 113, for operating the switch proper, depends from the closure 111 within the passage 110. It will be observed that the heat-responsive bi-metallic element 113 is exposed to

the heat radiated directly from the fuel burning in the combustion chamber itself and, therefore, a precise control of the operation of the furnace is obtained under those conditions where no heat is demanded by the media to be heated whereby the temperature of the fuel bed will be maintained sufficiently high to sustain continued combustion of the fuel but only at substantially the minimum rate of combustion over periods during which these conditions exist, which is necessary so to support combustion.

It is to be understood, of course, though we have illustrated and described our furnace as comprising heat insulating material for the purposes above set forth, the walls of the combustion chamber and passages are lined with fire brick or like heat-resistant material.

While we have described our invention in its preferred embodiments, it is to be understood that the words which we have used are words of description rather than of limitation. Hence, changes within the purview of the appended claims may be made without departing from the true scope and spirit of our invention in its broader aspects.

What we claim is:

1. A furnace of the character described comprising a combustion chamber within which fuel may burn, means defining a plurality of passages communicating with said combustion chamber and through which the gases of combustion may flow, one of said plurality of passages constituting a by-pass, a heat-transfer device included in a first of said plurality of passages and a heat-transfer device included in a second of said plurality of passages, said heat-transfer devices being adapted respectively to supply heat to a first and second medium, a valve operatively associated with each of said plurality of passages, valve-operating means, a first heat-responsive means responsive to the temperature of said first medium and a second heat-responsive means responsive to the temperature of said second medium for controlling respectively the valve associated with said first and second passage and both of said heat-responsive means being operable to control the valve associated with said by-pass passage to close the by-pass valve when either of the other valves are opened and to open said by-pass valve when both of the other valves are closed.

2. A furnace of the character described comprising a combustion chamber within which fuel may burn, means defining a plurality of passages communicating with said combustion chamber and through which the gases of combustion may flow, one of said passages including a heat-transfer device adapted to supply heat to a medium, means for controlling the flow of gases through said plurality of passages including a heat-responsive means responsive to the temperature of said medium, said flow control means being operable to pass substantially all of said gases to said heat-transfer device when a heat demand exists and to prevent a flow of gases to said heat-transfer device and to exhaust said gases through a second of said passages when no heat demand exists, a fan arranged to produce a forced flow of gases of combustion, an electric motor for driving said fan, said motor being controlled by said heat-responsive means, and means including a switch and a heat-responsive, actuating element therefor disposed in heat responsive relation to heat generated in said combustion chamber for controlling said motor.

3. A furnace of the character described comprising a combustion chamber within which fuel may burn, means defining a plurality of passages communicating with said combustion chamber and through which the gases of combustion may flow, one of said passages including a heat-transfer device adapted to supply heat to a medium, means for controlling the flow of gases through said plurality of passages including a heat-responsive means responsive to the temperature of said medium, said flow control means being operable to pass substantially all of said gases to said heat-transfer device when a heat demand exists and to prevent a flow of gases to said heat-transfer device and to exhaust said gases through a second of said passages when no heat demand exists, a fan arranged to produce a forced flow of gases of combustion, an electric motor for driving said fan, said motor being controlled by said heat-responsive means, and means including a switch and a heat-responsive, actuating element therefor disposed in direct heat responsive relation to heat radiated from the fuel burning in said combustion chamber for controlling said motor.

4. A furnace of the character described comprising a combustion chamber having a grate therein adapted to support a bed of fuel, means defining a plurality of passages communicating with said combustion chamber and through which the gases of combustion may flow, one of said passages including a heat-transfer device adapted to supply heat to a medium, means for controlling the flow of gases through said plurality of passages including a heat-responsive means responsive to the temperature of said medium, said flow control means being operable to pass substantially all of said gases to said heat-transfer device when a heat demand exists and to prevent a flow of gases to said heat-transfer device and to exhaust said gases through a second of said passages when no heat demand exists, a fan arranged to produce a forced flow of gases of combustion, an electric motor for driving said fan, means forming an air inlet opening for the admission of air beneath said grate, a valve for controlling the admission of air through said air inlet opening, electrical means for operating said valve, said motor and electrical means being controlled by said heat-responsive means to open said valve whereby to admit air beneath said grate when said motor is energized and to close said valve when the motor is de-energized, and means responsive to heat generated in said combustion chamber for controlling said motor and electrical means.

5. A solid fuel-burning furnace of the character described comprising a combustion chamber having a grate therein upon which solid fuel may burn, means defining a plurality of passages communicating with said combustion chamber above the grate therein and through which the gases of combustion may flow, a first of said plurality of passages including a heat-transfer device adapted for house-heating purposes and a second of said passages forming a by-pass for the direct exhaust of combustion gases from said combustion chamber, means for controlling the flow of gases through said plurality of passages, said control means being operable substantially to prevent the flow of gases through one of said passages when actuated to permit a flow thereof through the other passage, means for operating said control means, means for producing a forced flow of gases of combustion, and means

responsive to the temperature of the medium heated by said heat-transfer device for controlling the operation of said operating means and said means for producing a forced flow of gases; whereby combustion gases flow through said heat-transfer device only when a heat demand for house heating purposes exists.

6. A solid fuel-burning furnace of the character described comprising a combustion chamber having a grate therein upon which solid fuel may burn, means defining a plurality of passages communicating with said combustion chamber above the grate therein and through which the gases of combustion may flow, a first of said plurality of passages including a heat-transfer device adapted for house-heating purposes and a second of said passages forming a by-pass for the direct exhaust of combustion gases from said combustion chamber, means for controlling the flow of gases through said plurality of passages, said control means being operable substantially to prevent the flow of gases through one of said passages when actuated to permit a flow thereof through the other passage, means for operating said control means, means for producing a forced flow of gases of combustion, means forming an air inlet opening for the admission of air beneath said grate, a valve for controlling the admission of said air and operating means therefor, and means responsive to the temperature of the medium heated by said heat-transfer device for controlling the operation of said control-operating means, said flow-producing means and said valve-operating means; whereby combustion gases flow through said heat-transfer device only when a heat demand for house heating purposes exists.

7. A solid fuel-burning furnace of the character described comprising a combustion chamber having a grate therein upon which fuel may burn, means defining a plurality of passages communicating with said combustion chamber above said grate and through which the gases of combustion may flow, a heat-transfer device included in one of said plurality of passages and adapted to supply heat to a medium for house-heating purposes, a heat-transfer device included in a second of said plurality of passages and adapted to supply heat for domestic hot water supply purposes, and a third of said plurality of passages constituting a by-pass, valve means for controlling the flow of gases of combustion to said heat-transfer devices and through said by-pass, said valve means being operable substantially to prevent the flow of gases to said heat-transfer devices, and means including a first and second heat-responsive means responsive respectively to the temperatures of said medium and said domestic hot water supply to which heat is transferred by said heat-transfer devices for operating said valve means; said valve means being operable to positions permitting at all times an exhaust of said gases from the combustion chamber but to a position substantially preventing the passage of said gases through said by-pass when actuated to pass said gases to either or both of said heat-transfer devices and to a position permitting the passage of gases through said by-pass when preventing the passage thereof to both of said heat-transfer devices.

8. A solid fuel-burning furnace of the character described comprising a combustion chamber having a grate therein upon which fuel may burn, means defining a plurality of passages communicating with said combustion chamber

above said grate and through which the gases of combustion may flow, a heat-transfer device included in one of said plurality of passages and adapted to supply heat to a medium for house-heating purposes, a heat-transfer device included in a second of said plurality of passages and adapted to supply heat for domestic hot water supply purposes, and a third of said plurality of passages constituting a by-pass, valve means for

10 controlling the flow of gases of combustion to said heat-transfer devices and through said by-pass, said valve means being operable substantially to prevent the flow of gases to said heat-transfer devices, means for providing a forced flow of gases of combustion, and means including a first and second heat-responsive means responsive respectively to the temperatures of said medium and hot water supply for operating said valve means and said means for producing a forced flow of gases; said valve means being so constructed and arranged as to prevent a flow of gases through said by-pass when passing said gases to one or both of said heat-transfer devices and to pass said gases through said by-pass when preventing their flow to both heat-transfer devices.

9. A solid fuel-burning furnace of the character described comprising a combustion chamber having a grate therein upon which fuel may burn, means defining a plurality of passages communicating with said combustion chamber above said grate and through which the gases of combustion may flow, a heat-transfer device included in one of said plurality of passages and adapted to supply heat to a medium for house-heating purposes, a heat-transfer device included in a second of said plurality of passages and adapted to supply heat for domestic hot water supply purposes, and a third of said plurality of

30 35 40 45 50 55 60 65 70

passages constituting a by-pass, valve means for controlling the flow of gases of combustion to said heat-transfer devices and through said by-pass passage, and means including a first and second heat-responsive means responsive respectively to the temperatures of said medium and said domestic hot water supply for operating said valve means; said valve means being so constructed and arranged as to prevent a flow of gases through said by-pass when passing said gases to one or both of said heat-transfer devices and to pass said gases through said by-pass when preventing their flow to both heat-transfer devices.

10. A solid fuel-burning furnace of the character described comprising a combustion chamber having a grate therein upon which fuel may burn, means defining a plurality of passages communicating with said combustion chamber above said grate and through which the gases of combustion may flow, a heat-transfer device included in one of said plurality of passages and adapted to supply heat to a medium for house-heating purposes, a heat-transfer device included in a second of said plurality of passages and adapted to supply heat for domestic hot water heating purposes, and a third of said plurality of passages constituting a by-pass, valve means for controlling the flow of gases of combustion to said heat-transfer devices, means for producing a forced flow of gases of combustion, means including a first and second heat-responsive means responsive respectively to the temperatures of said medium and hot water supply for operating said valve means and controlling said means for producing the forced flow of gases; said valve

means being so constructed and arranged to prevent a flow of gases through said by-pass when passing said gases to one or both of said heat-transfer devices and to pass said gases through said by-pass when preventing their flow to both heat-transfer devices, and means responsive to heat generated in said combustion chamber for controlling said flow-producing means.

11. A solid fuel-burning furnace of the character described comprising a combustion chamber having a grate therein upon which solid fuel may burn, means defining a plurality of passages communicating with said combustion chamber above said grate and through which the gases of combustion may flow, one of said passages including a heat-transfer device adapted to supply heat to a medium, means for controlling the flow of gases through said plurality of passages including a heat-responsive means responsive to the temperature of said medium, said flow-control means being so constructed and arranged as to prevent a flow of gases through a first of said passages when passing gases through a second thereof and to pass gases through said first passage when preventing their flow through said second passage, means for producing a forced flow of gases of combustion, the operation of said last mentioned means being controlled by said heat-responsive means, and means responsive to heat generated in said combustion chamber for controlling the operation of said flow-producing means.

12. A solid fuel-burning furnace of the character described comprising a combustion chamber having a grate therein upon which solid fuel may burn, means defining a plurality of passages communicating with said combustion chamber above said grate and through which the gases of combustion may flow, two of said passages including heat-transfer devices adapted to supply heat to separate media, one for house heating

5 and one for domestic hot water heating purposes, means for controlling the flow of gases through said plurality of passages including two heat-responsive means responsive respectively to the temperature of the media heated by said devices, said flow-control being so constructed and arranged as to pass gases of combustion through one of said passages when preventing their flow to both of said heat-transfer devices, means for 10 producing a forced flow of gases of combustion, the operation of said last mentioned means being controlled by said heat-responsive means, and means responsive to heat generated in said combustion chamber for controlling the operation of said flow-producing means.

13. A solid fuel-burning furnace of the character described comprising a combustion chamber having a grate therein upon which fuel may burn, means defining a plurality of passages communicating with said combustion chamber above 15 said grate and through which the gases of combustion may flow, a heat-transfer device included in one of said plurality of passages and adapted to supply heat to a medium for house-heating purposes; a heat-transfer device included in a second of said plurality of passages and adapted to supply heat for domestic hot water supply purposes, and a third of said plurality of passages constituting a by-pass, and valve means including operating means therefor for controlling the flow of gases of combustion to said heat-transfer devices and through said by-pass; said valve means being so constructed and arranged as to substantially entirely cut off the flow of said gases through said by-pass when actuated to pass said gases to either or both of said heat-transfer devices and to permit the flow of said gases through said by-pass when actuated to prevent a flow of gases to both heat-transfer devices.
